(57) **CLAIM**

The ornamental design for a toy block, as shown and described.

DESCRIPTION

FIG. 1 is a front elevational view of the toy block showing my new design;

FIG. 2 is a rear elevational view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is an isometric view thereof, an opposite isometric view being identical thereto;

FIG. 8 is an isometric view thereof, in which a toy block in broken lines is provided to illustrate an example environment; and,

FIG. 9 is a perspective view thereof, in which two toy blocks in broken lines are provided to illustrate an example environment.

The broken lines depict environmental subject matter only and form no part of the claimed design.

The claimed toy block is an assembling block which can be combined with other assembling blocks to assemble a toy.
